UNITED STATES PATENT OFFICE.

ERNEST M. HUNT, OF QUINCY, MASSACHUSETTS.

ELECTRICAL CONNECTING DEVICE.

Application filed January 5, 1926. Serial No. 79,451.

This invention relates to an improved electrical connecting device which is capable of general use but which is especially adapted for radio apparatus. It is an object of the invention to provide a connecting device which is relatively simple and easy to construct, which makes a firm solid contact, which shields efficiently the live metallic members from accidental contact with other metallic parts of an apparatus, and which is durable.

Other advantageous features of construction will be apparent to one skilled in the art from the following description of the invention and from the drawing, of which,

Figure 1 shows in perspective and partly in section, another form of socket embodying the invention, and a plug connector adapted to cooperate therewith, the parts being separated.

Figure 2 shows in section the socket shown by Figure 1, the parts being assembled, the socket being engaged with the plug connector.

The same reference characters indicate the same parts in all of the figures.

The insulating casing of the socket is sectional and composed of rigid insulating material, such as bakelite.

The casing includes an inner section 27, having at one end a rigid internal annular seat 28, surrounding an orifice 29, which receives a flexible conductor 14, and at its opposite end a fixed internally threaded bushing 30, preferably of metal. The casing includes also an annular outer section 31, constituting an extension of the inner section, and provided with a sleeve 32, having an external thread engaging the internal thread of the bushing 30, the bore of the sleeve being internally threaded to engage an externally threaded fixed plug connector or binding post 33.

The enclosed contact member fixed to the flexible conductor 14 within the casing is designated by 34, and is formed to abut against the seat 28, to prevent separation of the socket from the flexible conductor.

The casing is adapted to turn freely on the conductor 14, during the operation of engaging the socket with the plug connector

33, until the connector contacts with the contact member 34, said member being then clamped firmly against the seat 28, by the plug connector.

The socket shown by the figure also prevents liability of short-circuiting contact between the contact member 34 and the contact member of another socket, the construction being such that the socket may be quickly and conveniently engaged with and separated from the plug connector 33, without twisting the flexible conductor during either operation.

I claim:

1. In an electrical connector, a socket comprising a sectional casing of rigid insulating material including an inner and an outer section, the inner section having at one end a rigid annular seat surrounding an orifice 70 which receives a flexible conductor, and at its opposite end a fixed internally threaded bushing, the outer section being annular and constituting an extension of the inner section, and provided with a sleeve having 75 an external thread engaging the internal thread of the bushing, and with an internal thread, an enclosed terminal contact member fixed to the flexible conductor within the casing, and abutting said seat to prevent 80 separation of the socket from the flexible conductor, said enclosed contact member being protected by the casing against short-circuiting contact with the contact member 85 of another socket, and an externally threaded plug connector, adapted to engage the internal thread of said sleeve, and have conducting and clamping contact with the terminal contact member, the socket being adapted to turn loosely on the flexible conductor, until the plug connector contacts 90 with the terminal contact member.

2. In an electrical connector, a socket comprising a sectional casing of rigid insulating material including an inner and an outer section, the inner section having at one end a rigid annular seat surrounding an orifice which receives a flexible conductor, and at its opposite end a fixed internally threaded bushing, the outer section being annular and constituting an extension of the inner section, and provided with a sleeve having an 100

external thread engaging the internal thread of the bushing, and with an internal thread to receive a plug connector, said outer section also overlying the outer end face of said sleeve, and an enclosed terminal contact member fixed to the flexible conductor within the casing, and abutting said seat to prevent separation of the socket from the flex-

ible conductor, said contact member being aligned with the thread bore of said sleeve 10 for clamping and conducting contact with a plug connector when screwed into the socket through the sleeve.

In testimony whereof I have affixed my signature.

ERNEST M. HUNT.
